UNITED STATES PATENT OFFICE.

WILLIAM H. BAUCH, OF LAPORTE, INDIANA, ASSIGNOR TO AMERICAN 3-WAY PRISM CO., OF LAPORTE, INDIANA, A CORPORATION OF PENNSYLVANIA.

PLASTER-SCREED.

1,248,440.

Specification of Letters Patent. Patented Dec. 4, 1917.

Application filed June 30, 1917. Serial No. 177,872.

To all whom it may concern:

Be it known that I, WILLIAM H. BAUCH, a citizen of the United States, residing at Laporte, in the county of Laporte and State of Indiana, have invented certain new and useful Improvements in Plaster-Screeds, of which the following is a specification.

This invention relates to improvements in 10 plaster screeds, such as are used to gage the plaster-thickness in plastering walls and to provide nail-receiving bodies of wood or other fibrous material to which the trim and wall fixtures may be attached. Such 15 screeds are commonly affixed to the support, such as a cement wall, by a dab of settable plastic, such as plaster of Paris, and are so placed that the wooden blocks have their outer surfaces in a desired plane. In so 20 placing the screeds, especially upon an uneven cement or concrete foundation, the thickness of the attaching adhesive-dabs may vary quite materially and in some instances the base of the screed must come 25 flush or very nearly flush with the foundation wall.

One object of my invention is to provide a screed that may be affixed with a minimum adhesive dab and, if need be, with its base 30 flush against or very close to the foundation.

A further object is the provision of such a device in a form which may be manufactured at low cost and which is of sturdy and rugged construction and efficient in use.

Still other and further objects will become readily apparent to those skilled in the art from the following description taken in conjunction with the accompanying drawings, wherein—

40 Figure 1 is a plan view of a metallic base blank;

Fig. 2 is a side elevation of the completed article;

Fig. 3 is an end elevation thereof;

45 Fig. 4 is a perspective view of the screed illustrating its method of attachment; and

Figs. 5, 6, 7 and 8 are views corresponding with Figs. 1, 2, 3 and 4, but showing a modification.

50 My improved screed, in common with others heretofore known, comprises in general, a metal base structure and a wooden block carried by the base. Distinctively from known practice I provide special constructions of block and base affording numerous

advantages, and more particularly I provide in the base recesses or chambers, rearwardly opening to afford pockets for the retention of a material amount of the plastic dab between the wall and the screed at selected 60 areas even when the base is jammed against the foundation wall, and also having openings through the metal base communicating therewith through which the plastic may protrude and "bond," all insuring against 65 accidental displacement or loosening of the screed before the layer of wall plaster is applied. Also, by this construction, I make the base plate strong and light, enabling very thin gage metal to be effectively used 70 without too great liability to bending, and have simplified the mechanical construction and the assembling operation.

Referring to the embodiment of my invention illustrated in Figs. 1 to 4, the wooden 75 block 10 is of generally rectangular form in plan, having a flat outer surface 11 of less area than its bottom, the end walls 12—12 being inclined and the side walls 13—13 likewise inclined and terminating at laterally extending flanges or wings 14 which run along the sides of the block at the bottom thereof for engagement with lips of the metal base.

As a blank the base is appropriately cut 85 for formation, with end portions to lie in a common plane, a center portion to lie in the same plane, and side portions to be ribbed so as to form, in the parts that will flank the wood block, bottom opening chambers 90 elevated preferably to about the same extent as the depth of the wood wings 14 of the block and having at their crests inwardly facing lips to overlie the wood block wings.

In the specific construction shown in Figs. 95 1 to 4, the thin metal base plate has two transverse openings 16, 16, separated by an intervening transverse strip 17 that connects the uninterrupted borders along the sides of the blank. Each of these openings 16 is so 100 shaped as to leave along its longer edges base-lips 18 and at its ends the inwardly projecting lips 19. The blank is then formed (in practice it may be accomplished by one operation) to shape the metal of the 105 side border beyond each end of each opening 16 into a rib, tapering (or curved) outwardly thereby to form in the plate four rearwardly opening pockets, 20, each pocket-forming rib having its crest bearing the in- 110

- wardly projecting retaining lip 19 positioned flat in parallelism with the base-end and suitably spaced therefrom snugly to receive a block-wing 14. In this formation 5 of the blank, of course, the overall length of the base structure is decreased, the base lips 18 being brought into close proximity for minimum loss of strength, and to give maximum bearing surface to the wood block.
- 10 10 Into the guide way thus formed between the contiguous ends of the ribs the wood block may be slipped endwise for adequate retention by the lips 19 overlying the wings of the block.
- 15 15 In the blank apertures 21 are formed at suitable intervals around the border portion—preferably both at the ends and sides—there being preferably certain of these apertures, 21^a, so located as to open 20 through the sides of the chambers 20, preferably close to, or insecting, partially, the horizontal bottom of the base.
- 25 As shown in Fig. 4 the plaster of Paris dab 22 is applied to the bottom side of the plate filling the chambers 20 and protruding through the openings 21 and 21^a so that even if the screed be pressed so hard against the supporting wall 23 as to squeeze the 30 plastic into a very thin layer or practically 35 squeeze it all out beneath the flat portions of the base, ribs of the plastic remain in the bottom opening pockets or chambers to cause adequate adhesion of the metallic base to the supporting wall.
- 40 35 In the construction shown in Figs. 5 to 8 I have illustrated a modified embodiment of the invention wherein the wooden block is the same, but the base is so constructed that when completed it provides a single large 45 central chamber 20' on each side of the wood block in lieu of the two narrower channels 20, and correspondingly a single wide lip 19' to overlie the block wing in lieu of the two separated wings 19 of Fig. 4. In the 50 blank for this form of construction, as illustrated in Fig. 5, the central opening 16' lies between the base lip 18' at its sides and the lips 19' at its ends, suitable cuts 17' effecting the desired severance between lips 18' 55 and 19' to permit the formation of the desired broad chambers 20'. The openings 21 and 21^a perform the same functions in this type of construction as in the other.
- The construction last described may, of 55 course, be made with a somewhat simpler

die than that first described, and offers other advantages, while the greater stiffness and wider separation of the points of retention of the wood block by the lips 19 gives same special advantages to the construction 60 shown in Figs. 1 to 4.

It will be apparent to those skilled in the art that I have illustrated two forms of embodiment of my invention especially with a view to indicating that wide changes in detail may be made without departure from the spirit of my invention and it will be apparent that many other and further changes may be made without departure from the spirit of my invention and within the scope 70 of the appended claims.

Having described my invention, what I claim is:—

1. A plaster screed comprising a wooden block having side portions shaped for engagement with lips and a sheet metal plate ribbed outwardly at opposite sides of the block to form bottom opening recesses to receive the plastic by means of which it is attached to a wall and providing at the 75 crests of said ribs lips inwardly projecting to engage the appropriate portions of the block.

2. A plaster screed comprising a wooden block having projecting wings at its bottom and a sheet metal plate having a central portion lying in a plane to give bearing to the block and flanking portions formed into ribs to provide bottom opening 80 chambers for the reception of plastic, each 90 such rib terminating at its inner end in a projecting lip to overlie a wing of the block.

3. A plaster screed comprising a wooden block having wings 14 near its bottom and a sheet metal plate having a central portion 95 lying in a common plane to underlie the block and side border portions flanking said block outwardly bent to form ribs, affording inwardly opening chambers for the reception of plastic, each such rib carrying an 100 inwardly projecting lip to overlie the corresponding wing of the block.

In testimony whereof I hereunto set my hand in the presence of two subscribing witnesses.

WILLIAM H. BAUCH.

In the presence of—
C. H. PASCHALL,
FLORENCE LINOP.
